Inventor,
Harry A. Hall,
By Joseph A. Minton
Attorney.

UNITED STATES PATENT OFFICE.

HARRY A. HALL, OF NEWCASTLE, INDIANA, ASSIGNOR TO HOOSIER MANUFACTURING COMPANY, OF NEWCASTLE, INDIANA, A CORPORATION OF INDIANA.

METAL TABLE-TOP-STRETCHING METHOD AND MEANS.

Application filed May 12, 1924. Serial No. 712,814.

To all whom it may concern:

Be it known that I, HARRY A. HALL, a citizen of the United States, residing at Newcastle, in the county of Henry and State of Indiana, have invented new and useful Improvements in Metal Table-Top-Stretching Methods and Means, of which the following is a specification.

Table tops stamped and pressed out of sheet metal, usually with depending edge-flanges joined to the plane body-surface by a raised bead or rib, and afterwards enameled, are much in use for kitchen cabinets, and the like, and require to be stretched and so held, on account of a generally warped and buckled condition of the product.

It has been proposed to reinforce the under side of the metal top to be stretched and straightened by placing a rectangular wooden frame closely fitted inside of the marginal flange, then placing clamping bars on the ends of the frame and table-top to draw the frame and top straight against a table or bench, then moving the side frame members apart by means of a jack and there retaining them by brace boards introduced angularly to the side members, and then driving them straight and afterwards so retaining them as permanent parts of the table-top.

The object of my invention is to eliminate the end clamping operation and combine the operation of jacking the side members apart with that of the introduction of the permanent transverse braces, which, by including braces at the ends instead of end frame members, cheapens the cost of the frame and also secures a more extended and therefore a better distribution of the force which separates the side members and stretches the metal table-top.

I accomplish the above, and other minor objects which will hereinafter appear, by the means illustrated in the accompanying drawing in which—

Figure 1 is a top plan view of my stretching bench and mechanism with a table-top in place and stretched, a portion of the mechanism being broken away; Fig. 2 is an end view of same; Fig. 3 is a cross section of a straightened table top, inverted, as taken on the line 3—3 of Fig. 1; Fig. 4 is a plan view of the under side of a table top showing the cross strips with a lapped

joint, a modification from Fig. 1; and Fig. 5 is a cross section taken on the line 5—5 of Fig. 4 showing by dotted lines the strips in position ready to be pressed into place and by solid lines the strips after the stretching operation is completed.

Like characters of reference indicate like parts in the several views of the drawing.

The metal table-top 4 has a marginal bead 5 and a depending rim flange 6, here shown as upwardly extending in the reversed position in which the top is placed, as shown, for the stretching operation. It is laid, thus reversed, upon the flat top 7 of a bench that is supported by legs 8. A pair of standards 9 extend upwardly of the top 7 at the rear of the bench and support a horizontal board 10, to the lower front edge of which a wide board 11 is swingingly secured by hinges 12. A forwardly extended lever 13 is fastened to the board 11 and provides a handle and leverage by which the board is swung downwardly with force, or purposes that will be hereinafter disclosed.

Narrow side-rails 14, 14, each having a longitudinal groove on their adjacent edges, are assembled in the inverted table-top 4, against the flange 6 at the sides of the table, with the grooved edges of the rails turned inwardly; and a series of transverse brace-strips 15, here shown as five in number and each made of two pieces separated by transverse joints 16 allowing the strips to break upwardly at the joints for insertions, are placed equal distances from each other, starting with the two outermost ones in contact with the end flange 6 of the top 4. Said brace-strips have tongues 17 at each end which are inserted in the corresponding grooves in the respective side rails 14. The breaks at the joints 16, in the strips 15, will first present the strips in side elevation, as shown in dotted lines in Fig. 2, with their angles at the joints all under the front part of the board 11. The board 11 will first have been swung upwardly, by means of lever 13, to the positions of the board and lever shown in dotted lines in Fig. 2, to permit of this assembly of the strips 15.

Preferably, and as here shown, a bearing piece 18, narrower than the board 11, is attached to the board 11 and bears upon the strips 15, at their joints, to concentrate any pressure.

The strips 15 are thus lowered at their

joints by lowering the lever until the two pieces of each strip are in alinement with each other, and are in uniform contact with the table-top.

- 5 In assuming the last described relation, the jointed strips exert a powerful toggle action to spread the side-rails 14 apart and stretch the metal table top. The rails 14, and the strips 15 are all allowed to remain 10 thus in the metal top to hold the top in this stretched condition. While the joints will not break again without the application of considerable force, I prefer to guard against such occurrence by fastening together the 15 ends of the pieces at the joints by appropriately driving the well known corrugated sheet metal fasteners 18 into them. Nails 19 may be used as in Fig. 4, when strips with lapped ends are employed.

20 This completes the operation of stretching a table-top, which, it will be noted, is very quickly and easily done.

Having thus fully described my invention, what I claim as new and wish to secure by Letters Patent by the United States is—

1. The herein described method of stretching sheet metal table-tops with side and end flanges, which consists of assembling the 30 top with side rails capable of sliding movement away from each other, placing braces each comprising two transversely divided parts breaking outwardly, between the side rails with the two outermost ones in contact 35 with the respective end flanges of the top, and applying pressure simultaneously to the braces at their joints to straighten the parts and slide the rails away from each other.

2. The herein described method of stretching sheet metal table tops with side and end flanges, which consists of assembling the top with side rails capable of sliding movement away from each other, placing three or 40 more braces each comprising two transversely divided parts breaking outwardly at the joints thus formed, between the side rails with the two outermost ones in contact with the respective end flanges of the top, applying pressure simultaneously to the 45 braces at their joints to straighten the parts and slide the rails away from each other,

and finally securing together the ends of the pieces at the joints of the braces so they will not break again.

3. A stretching device for sheet metal 55 table tops with side and end flanges, comprising a pair of side rails capable of sliding movement away from each other, a plurality of brace-strips each in two transversely divided parts breaking in a direction away from the table top at the resulting joints when first assembled on the table top, the two outermost brace-strips being in contact with respective end flanges of the top, and means to contact all of the joints and 60 simultaneously to force the parts into straight alinement with each other by pressure, to strengthen the broken joints and thereby slide the rails apart.

4. A sheet metal table top stretching device comprising a pair of side rails capable of sliding movement away from each other, a plurality of brace strips each in two transversely divided parts breaking in a direction away from the table top, at the resulting joints when first assembled on the table top, a hinged member adapted to simultaneously contact the broken joints of all of the brace strips, and a lever to move the hinged member against the joints to straighten the 70 brace strips and slide the rails apart.

5. A stretching device for a sheet metal table-top with flanges, comprising a bench upon which the inverted top is held while being stretched, a pair of side rails capable 85 of sliding movement away from each other placed against the flanges of the top, a plurality of brace strips each in two transversely divided parts breaking in a direction away from the table-top at the resulting joints, an upstanding bench member, a swinging member hinged to the upstanding bench member and adapted to simultaneously contact the broken joints of all of the brace strips and straighten the strip by a 90 swinging movement of said hinged member, and lever means for swinging the hinged member.

Signed at Newcastle, Indiana, this the 28th day of April, 1924.

HARRY A. HALL.
